CLAIM

The ornamental design for an anti-skid tire traction unit, as shown and described.

DESCRIPTION

FIG. 1 is a front elevational view of an anti-skid tire traction unit showing my new design;

FIG. 2 is a rear elevational view thereof;

FIG. 3 is a top plan view thereof;

FIG. 4 is a bottom view thereof;

FIG. 5 is a right side elevational view thereof, the left side being a mirror image of that shown; and,

FIG. 6 is an enlarged fragmentary front elevational view thereof.

FIG. 1

FIG. 2

FIG. 3

FIG. 4

FIG. 5

FIG. 6
